UNITED STATES PATENT OFFICE.

WINTHROP L. JACOBS, OF EAST ORANGE, NEW JERSEY, ASSIGNOR TO THE
LOWELL MANUFACTURING COMPANY, OF MASSACHUSETTS.

DESIGN FOR CARPET.

SPECIFICATION forming part of Design No. 24,979, dated December 10, 1895.

Application filed November 11, 1895. Serial No. 568,636. Term of patent 31 years.

To all whom it may concern:

Be it known that I, WINTHROP L. JACOBS, a citizen of the United States, and a resident of East Orange, in the county of Essex and State 5 of New Jersey, have invented a new and original Design for a Carpet and Border, of which the following is a specification.

This invention comprises two parts, namely: the design A for a carpet, and the design B 10 for a border; and I do hereby declare that the drawing accompanying this specification conveys to any one a clear understanding of the same, and is sufficient to enable such person to use my invention. 15 The design A consists of closely-associated conventional figures of different sizes, some of whose elements project into and form parts of contiguous figures.

The design B consists of three panels running lengthwise, the inner panel being made 20 up of curvilinear figures characterized by an outline of small conventional flower-forms

and a central conventional medallion or ornament, the middle panel being made up of conventional figures having the general outline of a pyramid, and the outer panel being made up of ornamental figures of nondescript pattern.

What I claim, and desire to secure by Letters Patent, is—

1. In a design for a carpet, the body A, substantially as shown.
2. In a design for a carpet, the border B, substantially as shown.
3. The design for a carpet, comprising the body A and the border B, substantially as shown.

In testimony whereof I have signed my name to this specification in the presence of two subscribing witnesses.

WINTHROP L. JACOBS.
